UNITED STATES PATENT OFFICE.

GEORGE A. WELD, OF WINCHESTER, MASSACHUSETTS.

SUSPENDER-BUCKLE.

No. 889,495.

Specification of Letters Patent.

Patented June 2, 1908.

Application filed December 19, 1907. Serial No. 407,180.

To all whom it may concern:

Be it known that I, GEORGE A. WELD, a citizen of the United States, residing at Winchester, in the county of Middlesex and State 5 of Massachusetts, have invented certain new and useful Improvements in Suspender-Buckles; and I do hereby declare the following to be a full, clear, and exact description of the invention, such as will enable others 10 skilled in the art to which it appertains to make and use the same.

My invention relates to buckles, but more particularly has reference to suspender buckles so constructed that the webbing may 15 be disposed in such manner that said buckles will be "rustless."

The object of my invention is to provide a buckle in which the clamping of the webbing shall be effected against a resiliently 20 yielding bar or surface, and my invention consists of certain details of construction and combination of parts such as will be herein-after fully described and then particularly pointed out in the claims which conclude 25 this specification.

Referring to the drawing Figure 1 is a view in elevation of my preferred style of buckle having a webbing attached thereto—Fig. 2 a view in elevation of my preferred 30 style of buckle without the webbing—Fig. 3 a cross section showing the buckle clamped against the webbing, and Fig. 4 an elevation of a modified form of my improvement.

Similar numbers of reference denote like 35 parts in the several figures of the drawing.

My improved buckle is made from wire and comprises a closed loop at the bottom, a space for the webbing above said loop, pintles formed by the extreme ends of the 40 wire immediately beyond said space, and a clamping lever pivoted to said pintles and adapted to coact with the upper surface or bar of said loop.

In making the frame of my improved 45 buckle, the wire is bent to form the bottom and ends of the loop, the free ends of the wire being then bent inwardly beyond each other and in the same horizontal plane to provide a clamping surface 2, the ends being 50 finally bent inwardly in planes beyond the ends of the loop to form the sides 3 of the webbing space, and thence inwardly to provide pintles 4. The top or upper bar of the loop thus formed will afford a resiliently 55 yielding clamping surface, and I provide a clamping lever 5 with ears 6 that are curled

around the pintles 4 thereby affording a pivotal connection for said lever which latter has a lip 7 preferably serrated, which lip, when the lever is properly operated, coacts 60 with said clamping surface to firmly bind the webbing.

One end of the webbing 8 is passed from the rear of the buckle through the space 9 and thence down over the face of the buckle 65 and is secured to the body of the webbing in any suitable manner as by stitching, the main webbing being then passed through the space 9 from the front of the buckle, so that it will be clear that none of the metal portions 70 at the back of the buckle will come in contact with the clothing of the wearer, and my buckle, therefore, possesses the advantages of being "rustless" so-called. When the clamping lever is forced downwardly the lip 75 7 will coact with the clamping surface 2 to bind the webbing firmly, and if the webbing has considerable thickness this clamping surface will yield when the clamping lever is operated so that there can be no undue straining 80 of the buckle. The object of forming this loop with its upper boundary composed of its side wires extended toward and beyond each other is solely to provide a resiliently yielding clamping surface to coact with the clamping 85 lever, and this is the novel feature involved in my present invention. Two of these resilient loops 1 may be formed at the lower portion of the frame, if desired, as shown at Fig. 4, but I prefer the construction 90 shown at Fig. 2.

Having thus described my invention what I claim as new and desire to secure by Letters Patent is:—

1. A buckle made from wire and comprising 95 a closed loop at the bottom, a space for the webbing above said loop, pintles formed by the extreme ends of the wire immediately beyond said space, and a clamping lever pivoted to said pintles, the wire being bent to 100 form the bottom and ends of the loop, the free ends of the wire being then bent and extended inwardly beyond each other and in the same horizontal plane, said ends being then bent upwardly in planes beyond the 105 ends of the loop and thence inwardly to form said pintles, whereby the top of the loop will afford a resiliently yielding clamping surface to coact with said clamping lever.

2. A buckle comprising a frame made of 110 wire formed into a closed loop at the bottom of the frame, the upper boundary of said

loop being formed by bending the side wires of the loop inwardly beyond each other and disposing the wires thus bent side by side to afford an unbroken clamping surface whose thickness from top to bottom is substantially equal to the gage of the wire itself whereby said upper part of the loop will afford an unbroken and resiliently yielding clamping surface, the ends of the wire being then bent at points beyond the sides of the loop upwardly and inwardly to form respectively a passage

for the webbing and pintles, and a clamping lever pivoted around said pintles and having at its lower edge a clamping lip adapted in closed position to coact with said clamping ¹⁵ surface.

In testimony whereof I affix my signature in presence of two witnesses.

GEO. A. WELD.
